UNITED STATES PATENT OFFICE.

ENRIQUE VINCKE, OF BARCELONA, SPAIN, ASSIGNOR TO MANUFACTURAS DE CORCHO,
S. A., OF BARCELONA, SPAIN.

CORKWOOD FACING FOR MANGLE ROLLS AND THE LIKE.

Application filed January 12, 1923. Serial No. 612,298.

An object of this invention is to provide a mangle for ironing and other laundering and similar purposes with a facing capable of effecting the desired pressure and affording also sufficient yieldability to permit buttons and other fragile or rigid adjuncts of clothing and the like to pass therethrough without substantial injury.

Heretofore, as generally practiced at the present time, it has been customary in mangle machines to apply felt layers or other elastic material enclosed in windings of linen, duck or the like on the cylindrical face of a mangle roll; however, the steam released in the ironing operation is absorbed by the felt and fabric layers and the heat attending the ironing operation, effect continued shrinkage and hardening of the felt. Such procedure has been improved upon by securing blocks or strips of corkwood to the cylindrical surface of the iron or steel mangle roll.

However, natural cork wood in such good quality as to give satisfactory results, is limited to blocks or strips of about 12 inches in length by 6 inches in width and considerable time is required in gluing or otherwise securing the required number of these on the cylinder and in cutting the contiguous edges of the cork strips to obtain close fit.

Pursuant to the present invention, the facing of the mangle iron is provided in the form of a complete ring of cork material fully completed at the place of manufacture and requiring but the mere slipping on of the ring over the mangle iron. Such ring is preferably formed of an inner ring of composition cork compressed and molded to be substantially inexpandable and non-contractible under temperature variations and an outer ring of natural cork wood secured to the inner ring of composition cork, such outer ring being formed of blocks of natural cork wood, the inner faces of which are shaped correspondingly and secured to the outer face of the inner ring of composition cork, the outer face of the outer ring of natural cork wood being eventually protected by a moisture and heat proof lacquer, varnish or the like. By the procedure of the present invention, the facing for the mangle irons may be formed of sections, which sections are slid on and keyed or

otherwise secured to a mangling iron and another section partially slid out of position.

Further features and objects of the invention will be more fully understood from the following detail description and accompanying drawings, in which—

Fig. 1 is a side elevation of a roll of a mangling machine provided with a facing embodying my invention;

Fig. 2 is a sectional elevation on line 2—2, of Fig. 1;

Fig. 3 is a detail sectional elevation of the facing taken on line 3—3 of Fig. 2; and

Fig. 4 is a detail side elevation of Fig. 1, showing a section of the facing removed and another section partially moved out of position.

Referring to the drawings, the roll 10 represents a roll of a mangling machine or other form of laundering apparatus and the like.

The facing 11, is formed of sections denoted 12, 13, 14, 15, 16 as illustrated in Fig. 1, and such sections are longitudinally retained in position on the roll 10 by means of the end clamps 17, 18.

Each section is preferably formed of an inner ring 20, constructed of composition cork, formed of molded and compressed granules or particles of cork wood bonded to one another to be inexpandable under increase of temperature and moisture, as for example as is set forth in the United States Patent No. 484,345, granted to J. T. Smith, under date October 11, 1892. Preferably, the inner surface of the ring 20 is non-circular, such as the key surface 21 corresponding to and coacting with the key surface 22 formed on the surface of the mangle roll 10, see Fig. 4.

To the inner ring 20 of composition cork is applied the outer ring 23 of natural cork wood, as in the form of blocks, having their inner faces 24 conforming to the outer face of the ring 20 and secured thereto in any suitable manner, and the mutually engaging, lateral faces of the blocks 23, shaped to conform to one another and secured together. The outer faces of the blocks and accordingly of the outer ring 23 are shaped to the desired cylindrical form.

Preferably, a coating of waterproof material is applied to the outer face of the ring 23 to safeguard against the entry of

absorption of moisture from the articles laundered in the mangling machine. Sheet-
ing of cotton or linen may be applied over
the natural corkwood ring, as will be under-
stood.

- By means of the above arrangement, the required number of sections of my improved facing are slipped on the mangling roll 10 and set in position by means of the end 10 clamps 17, 18, to prevent displacement of the sections longitudinally of the roll 10. Circumferential displacement of the sections is prevented by the keying effected by the conjoint faces 21, 22.
- 15 If it is desired to replace any section, an end clamp, such as the left-hand end clamp 18, is removed from the mangling roll 10, see Fig. 4, and the section desired to be removed, say the section 15, is slid longitudinally to the left of the roll 10, after removing the end section 16, see Fig. 4.

The blocks 23 of natural cork wood are preferably keyed to the inner ring 20 of composition cork by means of the elevations 25 27 in the outer face of the inner ring 20 and corresponding depressions 28 on the inner faces 24 of the blocks 23.

The above described invention provides for the desired rigidity coupled with yielding 30 ability for ironing garments or the like of linen, cotton, and like fabrics while at the same time permitting buttons and like ad- denda to pass without substantial injury between the mangling roll and the heated 35 bed of steel or the like.

In the presence of heat and moisture, incident to the ironing operation, the inner ring maintains its diameter and the adhesive 40 between the inner ring and the outer surface of the outer ring is protected from moisture. The outer cylindrical surface of

the outer ring lends itself readily to the linen or cotton covering and enhances the ironing operation.

Pursuant to the above, the facing or sections of facing for the mangling rod are advantageously completed in the place of manufacture and are fully prepared for ready mounting on the mangling roll, even by unskilled help. The invention is also 45 50 55 advantageous in affording the ready substitution of any particular section without loss of the facing as a whole.

For certain uses, the inner core of composition cork may be substituted by molded paper pulp, or molded asbestos composition, or by certain metals and the like, to which inner core, the outer core of natural cork wood is applied as hereinabove set forth.

Whereas I have described my invention 60 by reference to specific forms thereof it will be understood that many changes and modifications may be made without departing from the spirit of the invention.

I claim:—

1. A new article of manufacture comprising a unit for a facing of mangling rolls and the like, formed of an outer ring of blocks of natural corkwood permanently secured to one another and to an inner ring 70 of molded, moisture and heat resisting composition cork.

2. A new article of manufacture comprising a unit for a facing of a mangle roll or the like, formed of an outer ring of blocks of natural corkwood permanently secured to one another and to an inner integral ring of molded, moisture and heat resisting cork material.

In testimony whereof I have signed this 80 specification this 9th day of January, 1923.

ENRIQUE VINCKE.
